UNITED STATES PATENT OFFICE.

JOHN BIGELOW, OF PHILADELPHIA, PENNSYLVANIA.

MACHINE FOR SEWING AND TRIMMING FABRICS.

SPECIFICATION forming part of Letters Patent No. 244,530, dated July 19, 1881.

Application filed September 29, 1880. (Model.)

To all whom it may concern:

Be it known that I, JOHN BIGELOW, a citizen of the United States, residing at Philadelphia, in the county of Philadelphia and State of Pennsylvania, have invented certain new and useful Improvements in Irregular-Stitch Sewing-Machines with Trimming Attachments; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the accompanying drawings similar letters of reference indicate like parts.

Figure 1 is a top view, showing the combination, with the cloth-plate of a sewing-machine, of a swinging tongued presser-foot, with mechanism for actuating the same, and a trimming device; also their relation to the needle and the feed. Fig. 2 is a side elevation, showing the swinging tongued presser-foot and its connection with its actuating device, also a trimming device, feed, needle, and the thread-looping device of a sewing-machine.

The object of the present invention is to produce a combination of mechanism adapted, among other things, to make the "cut hose," patented in Reissue Letters Patent No. 9,113, dated March 9, 1880. I produce the zigzag or irregular stitch therein required by means of a tongue attached to or forming part of the presser-foot, and so arranged that by swinging or vibrating the presser-foot the tongue is moved with it. The needle is thus enabled to make its stitch, alternately, first on one, then on the other, side of said tongue, which is tapered, so that as the material is moved along by the feed the stitch made over it easily slides off, yet is retained long enough to cause the material to follow its vibrations and be presented to the needle in a way which will make the line of sewing zigzag or irregular. I add to this zigzag-sewing mechanism the trimming device shown and described in my previous applications, and the combination will produce the cut-hosiery seam, patented as aforesaid.

For the purpose of illustration I have shown

my device applied to a Wilcox & Gibbs sewing-machine. It consists of a tongued presser-foot, (swinging on the presser-bar,) which is positively actuated by means of levers and a cam geared to the driving-shaft of the machine.

At the end D² of the presser-bar D³, Fig. 2, I attach the presser-foot D by any suitable device which will allow it to conform to the raising and lowering of the bar D³, and yet be free to make a laterally swinging or vibrating movement. At the point C, Figs. 1 and 2, forward of the swinging point D², by means of a pin, the presser-foot D is connected with a bar, B, which, in turn, is attached at A', Fig. 1, by a swinging joint to the bar A, which, by means of gearing and a cam, is reciprocated, when the feed is in action, in a direction alternately to the right and the left of the line of the same.

The connection of the bar B with the presser-foot D at C is suitably arranged to allow the foot to be raised and lowered, as is required for putting in or removing material from the machine.

At the point D', Fig. 1, of the presser-foot D, I attach a tongue projecting beyond and behind the needle, with a clearance for the needle on either of its sides, and so shaped that the stitches formed over it can be easily drawn off as the material is fed along beneath it, yet be retained long enough to oblige the material beneath it and secured to it by the stitch to conform to the alternate vibrations which it receives from the presser-foot D through the rod B, bar A, and its connections, as described.

The trimming device is similar to that described by me in other pending applications, filed August 19, 1880, and having serial numbers 15,651 and 15,669; but its combination with the tongued swinging or vibrating presser-foot as described is, I believe, new.

The material is placed beneath the presser-foot the same as in the ordinary machine, there being no change in the needle or the feed. The first stitch is made on one side of the tongue D'. When the needle has left the work and the feed is taking place the tongue D' is moved laterally toward the side on which the stitch was made. Assisted by the threads of the stitch the material beneath it is sufficiently

removed laterally by the tongue to allow the needle to perforate it back of and to one side of its previous perforation. At the next stitch 5 back to its original line of sewing. In this way, by successive lateral movements alternately to the right and left of the material carried by the tongue, the line of sewing is made zigzag. As soon as the stitches made over and across the tongue D' leave the same, the forward movement of the material by the feed becomes straight. At this point it passes into the trimming device, which is adjusted 15 near to or away from the line-opening, the surplus material is trimmed off, and the seam described in said Reissue Letters Patent is made.

Instead of the presser-foot being attached to and swinging on the presser-bar, it can be 20 reciprocated in a manner shown in my Letters Patent Reissue No. 9,112, March 9, 1880.

Since the vibrations of the presser-foot, when driven at a high speed, has a tendency to dazzle the vision of the operator, a shield can be 25 added which will hide its movements, yet not interfere with the guidance of the work.

In the trimming device I introduce a link-connection, as shown at T, Fig. 2, with the feed mechanism, as an improvement over the connection previously shown. 30

What I claim as new, and desire to secure by Letters Patent, is—

1. A swinging or vibrating presser-foot, having a tongue, substantially as and for the purpose described. 35

2. The combination, with the stitch-forming mechanism of a sewing-machine, of a swinging or vibrating tongued presser-foot, substantially as and for the purposes described.

3. The combination, with the stitch-forming mechanism of a sewing-machine, of a swinging or vibrating tongued presser-foot and a trimming device, substantially as and for the purpose described. 40

4. In testimony whereof I affix my signature 45 in presence of two witnesses.

JOHN BIGELOW.

Witnesses:

JAMES GREENWOOD,

A. J. WHITTIER.
